(57) **CLAIM**

I claim the ornamental design for a hose clip, as shown and described.

DESCRIPTION

FIG. 1 is a perspective view of a clip according to the invention.

FIG. 2 is a top view of the clip of FIG. 1.

FIG. 3 is a right side view of the clip of FIG. 1.

FIG. 4 is a front view of the clip of FIG. 1; and,

FIG. 5 is a rear view of the clip of FIG. 1.

The left side view of the clip is a mirror image of the right side view, and the bottom view of the clip is a mirror image of the top view. Therefore, the left side and bottom views have been omitted.

1 Claim, 2 Drawing Sheets

FIG. 1**FIG. 2**

FIG. 3

FIG. 4

FIG. 5
